US00D849767S

(12) **United States Design Patent** (10) Patent No.: **US D849,767 S**
 Mok et al. (45) Date of Patent: **** May 28, 2019**

(54) **DISPLAY SCREEN WITH GRAPHICAL USER INTERFACE**

(71) Applicant: **Google Inc.**, Mountain View, CA (US)

(72) Inventors: **Pui See Priscilla Mok**, San Francisco, CA (US); **Christopher Johnson**, Alviso, CA (US); **Marco Quiros Viquez**, San Jose, CA (US); **Daniel Lee**, Stockholm (SE); **Armando Miraglia**, Stockholm (SE); **Alex Usberg**, Stockholm (SE); **Carolina Sartorius**, Stockholm (SE)

(73) Assignee: **GOOGLE LLC**, Mountain View, CA (US)

(**) Term: **15 Years**

(21) Appl. No.: **29/596,419**

(22) Filed: **Mar. 8, 2017**

(51) LOC (11) Cl. **14-04**

(52) U.S. Cl.

USPC **D14/486**

(58) **Field of Classification Search**

USPC **D14/485-495**

(57) **CLAIM**

The ornamental design for a display screen with graphical user interface, as shown and described.

DESCRIPTION

FIGURE is a front view of a display screen with graphical user interface showing our new design.

The broken lines of uneven length show the display screen and form no part of the claimed design. The broken lines of even length illustrate portions of the display screen with graphical user interface that form no part of the claimed design.

1 Claim, 1 Drawing Sheet
